US0D1015552S

(12) **United States Design Patent** (10) Patent No.: **US D1,015,552 S**
(45) Date of Patent: ** Feb. 20, 2024

(54) **ELECTROSTIMULATION APPARATUS**

(71) Applicants: **ASSISTANCE PUBLIQUE—HOPITAUX DE PARIS**, Paris (FR); **UNIVERSITE VERSAILLES ST QUENTIN YVELINE**, Versailles (FR)

(72) Inventors: **Guillaume Bao**, Clichy (FR); **Eric Azabou**, Meulan (FR)

(73) Assignees: **ASSISTANCE PUBLIQUE—HOPITAUX DE PARIS**, Paris (FR); **UNIVERSITE VERSAILLES ST QUENTIN YVELINE**, Versailles (FR)

(**) Term: **15 Years**

(21) Appl. No.: **29/832,582**

(22) Filed: **Mar. 29, 2022**

(30) **Foreign Application Priority Data**

Sep. 30, 2021 (EM) 008712343-0001

(57) **CLAIM**

The ornamental design for an electrostimulation apparatus, as shown and described.

DESCRIPTION

FIG. 1 is a front perspective view of an electrostimulation apparatus, showing our new design;

FIG. 2 is a front view thereof;

FIG. 3 is a rear thereof;

FIG. 4 is a left side view thereof;

FIG. 5 is a right side view thereof;

FIG. 6 is a bottom view thereof; and,

FIG. 7 is a top view thereof.

The broken lines in the figures illustrate portions of the electrostimulation apparatus that form no part of the claimed design.

1 Claim, 5 Drawing Sheets
